WEFT-REPLENISHING MECHANISM FOR LOOMS.

1,149,550.

Specification of Letters Patent. Patented Aug. 10, 1915.

Application filed February 19, 1912. Serial No. 678,688.

To all whom it may concern:

Be it known that we, JOHN WHITTAKER, RICHARD BRADSHAW, and JOSEPH BRIGGS, subjects of the King of the United Kingdom of Great Britain and Ireland, and residing at Wellington Mill, Rishton, near Blackburn, in the county of Lancaster, England, have invented new and useful Improvements in Weft-Replenishing Mechanism for Looms, of which the following is a specification.

Our invention relates to weft-replenishing mechanism for looms and has for its object an improved magazine for holding the cop spindles, in which the cop spindles are fed downward by gravity into the position from which they are transferred into the shuttles.

In the accompanying drawings:—Figure 20 1 is a back elevation of the lower portion of the magazine. Fig. 2 is an elevation of the right-hand side of Fig. 1 showing the transferrer and the slay and shuttle in section. Fig. 3 is a plan of the magazine with 25 the jaws closed, the escapement arm being omitted, and Figs. 4 and 5 are horizontal sections of the magazine taken across the lines B B and C C respectively of Fig. 2.

In the following description the terms 30 "right-hand" and "left-hand" refer to the right and left hands of the operator standing in front of the loom and not to the right and left hand ends of Fig. 1. Similarly "forward" and "backward" mean "toward 35 the front" and "toward the back" of the loom.

Referring to the drawings, 34 is the slay, 35 the shuttle with front and back sides 93 and 92, 37 is the cop spindle magazine, 38 40 a cop spindle in the magazine, 39 the transferrer pivoted on its shaft 40.

The magazine 37 which is supported on the breast-beam by the bracket 52, consists of a rectangular tube with a slot on the 45 right-hand face. The inside is so shaped that the heels of the cop spindles fit closely in it, while the skewers pass through the slot. When the heels of the cop spindles are of a different form to that shown, the 50 shape of the inside of the magazine tube must be correspondingly modified. The heels of the cop spindles rest on one another, the lowest cop spindle being supported by the upper edge of an escapement 53 which 55 is pivoted to the magazine at 54. An arm

55, attached to the escapement 53, is pivoted to a link 56 which is pivoted to a pin 57 attached to the transferrer.

This connection between the transferrer and the escapement 53 is such that, when the transferrer is operated to transfer a cop spindle into the shuttle, the upper pallet of the escapement is moved away from under the lowest cop spindle heel, thus allowing the cop spindle to fall past this pallet; at 60 the same time the lower pallet is brought into the path of the cop spindle heel and consequently prevents its further fall. On the return motion of the transferrer, the escapement 53 is brought back to its normal 65 position, and the cop spindle held by the lower pallet is allowed to fall while the upper pallet retains the cop spindle next above it.

Now it has been found that the heels of the cop spindles sometimes jam in the magazine instead of falling down it when the cop spindle is transferred. A mechanism therefore has been introduced to insure every cop spindle falling down in the magazine so as to rest either on the cop spindle immediately below or on the retaining device. This mechanism is shown in Figs. 1, 2 and 3. The left-hand wall of the magazine has a vertical groove in which a strip 74 is capable of sliding up and down. A pin 75 fixed to the strip 74 passes through a slot 76 in the wall of the magazine and is acted on by a spring 77 tending to pull the pin upward. This pin 75 therefore serves to keep the strip 74 in place and the spring 77 70 tends to keep the latter at the higher limit of its travel. Preferably two such pins, slots and springs are employed, one near the top and the other near the bottom of the magazine. Now the cop spindle tends to 75 jam in the magazine because the free right-hand end outside the magazine tends to fall more quickly than the heel which is retarded by the friction against the walls of the magazine. The cop spindle then becomes slightly inclined with its tip pointing 80 downward, so that the heel of the cop spindle is held in the magazine by the lower point of its left-hand end touching the strip 74 and the upper portion of its right-hand 85 end or of the right-hand ring touching the right-hand wall of the magazine or the sides of the grooves 121 and 122 in the front and back walls respectively. If, when the cop spindle is jammed in this position by 90

110

reason of the friction between the contacting points, the strip 74 be moved downward, the friction between the strip 74 and the heel of the cop spindle tends to draw the 5 left-hand end of the heel downward and so level the cop spindle and release it from the position in which it was jammed so that it falls into its proper position. The requisite downward motion of the strip 74 is given 10 to it every time that a cop spindle is transferred, by a rod 78 fixed to the transerrer, striking a pin 79 fixed to the strip and moving the pin and the strip downward against the action of the spring 77, which latter re- 15 turns the strip to its normal position on the return stroke of the transerrer.

The device may be constructed in other ways, the essential feature of the device being that the surface against which the left-hand end of the heel of the cop spindle rests, be moved downward, or that the surface against which the right-hand end rests be moved upward.

The main portion of the magazine so far 25 described is applicable to many forms of weft-replenishing mechanism, the means of working the escapement varying according to the particular mechanism employed. Also, when the transerrer is such as to take 30 the cop spindles from their lowest position in this main portion of the magazine, the escapement mechanism can be dispensed with.

The lower portion of the magazine in 35 which a single cop spindle is retained in the path of the transerrer and which serves also to guide the cop spindle into the shuttle, will be described as designed for use with weft-replenishing mechanism in which the cop spindle is introduced into the shuttle 40 from above, passing under or partially under the loom spindle, and, wherein, in order that the loom spindle may be able to advance sufficiently the portion of the magazine which guides the back side of the cop 45 spindle, has to be pivoted so as to move forward and, in some cases, pass the front portion when it is not giving passage to a cop spindle and so as to swing backward only when giving passage to a cop spindle. 50 These requirements are satisfied and the cop spindle always retained parallel to the axis of the shuttle by retaining throughout this portion of the magazine, as far as is 55 possible, the shape of a rectangular tube as in the upper portion of the magazine.

The front face of the magazine is continued downward nearly to the level of the shuttle, but its inside guiding surfaces are 60 curved as seen in Fig. 2 to guide the cop spindle into the shuttle. Also a slot is cut in the center of the front face to admit the transerrer. The back face of the magazine is cut away a little below the escapement, and 65 from here to the level of the shuttle, the cop spindle is guided by the flap with jaws 60

and 61, pivoted at 64, which is normally kept forward by the spring 65. At the level C C, where Fig. 5 is a section, it will be seen that the four walls of the magazine have been divided up into four jaws 58 and 59 at 70 the front and 60 and 61 at the back, these jaws being a continuation of the four corners of the upper portion of the magazine and retaining the cop spindle parallel to the shuttle, in the same way as does the rectangular tube of the upper portion of the magazine, by the surfaces 67, 68 and 69 bearing on the sides of the cop spindle heel, and the surfaces 70, 71, 72 and 73 bearing on the two ends of the cop spindle heel. The bearing 75 surface for the side of the cop spindle heel on the jaw 60 is not necessary because the front edge of the jaw bears against the skewer of the cop spindle. The transerrer moves in the space between the two front 80 jaws 58 and 59 and in that between the two back jaws 60 and 61.

Fig. 4, which is a section along the line B B, shows the bearing surface of the jaws of the magazine at the point where the cop spindle is about to enter the shuttle. The back jaw 60 is so shaped as to pass to one side of the rib 66 of the front jaw 58 when a cop spindle is not passing between the jaws, so that its back edge is no farther back than 95 the back edge of the front jaw, 58. Similarly the back jaw 61 passes to one side of the front jaw 59. The retaining surfaces here are the same as at the level C C, except that the support for the end of the cop 100 spindle heel has been transferred from the surface 72 of the jaw 59 to the surface 73 of the projecting portion of the jaw 61; the back retaining surface 69 does not reach as far as the level B B because, in the construction shown, the proximity of the loom 105 spindle 62 does not admit of it. At the back therefore the cop spindle is retained only by the jaw 60 acting on the skewer.

As shown in Fig. 2 the loom-spindle 62 is 110 nearly touching the jaw 61, but as soon as the cop spindle begins to leave the jaws of the magazine and enter the shuttle, the back jaws come forward, passing to the side of the front jaws and so enable the loom 115 spindle to come farther forward as the slay continues its forward course while the cop spindle is being pressed home into the shuttle.

In the case of ring weft cop spindles, 120 where it is not possible to obtain a bearing surface at the right-hand end of the heel, the bearing surface afforded by the right-hand ring of the heel may be utilized. The right-hand sides of the grooves 121 and 122 125 then act as the right-hand wall of the magazine and in this case the same magazine will retain mule cop spindles, and ring weft cops on pirns. This form of magazine has three great advantages. First, the tips of the 130

cop spindles are entirely free, so that the weft, during transfer of the cop spindle, does not rub against any surfaces liable to cut or break it. Secondly, cop spindles with only a small quantity of weft are held as efficiently as full cop spindles. Thirdly, the same magazine is capable of holding both mule cop spindles and ring weft cop spindles.

10 Having described our invention, we declare that what we claim and desire to secure by Letters Patent is:—

1. A cop spindle magazine for weft-replenishing mechanism for looms, having 15 surfaces adapted to retain and guide the cop spindle by their heels substantially parallel to the axis of the shuttle, one of which engages the heel ends of the cop spindles and is movable in a direction to level and therefore 20 by release any cop spindle which may be jammed in the magazine.

2. In weft-replenishing mechanism for looms, the combination with a magazine and 25 surfaces therein adapted to retain and guide the cop spindles by their heels substantially parallel to the axis of the shuttle, one of the said surfaces being one surface of a 30 bar engaging the heel ends of the cop spindles and movable in a direction to level a cop spindle in the magazine, of means positively operating the bar to move it in one direction, and a spring to move it in the other direction.

3. In weft-replenishing mechanism for 35 looms, the combination with a magazine and surfaces therein adapted to retain and guide the cop spindles by their heels substantially parallel to the axis of the shuttle, one of the said surfaces being one surface of a bar eng- 40 gaging the heel ends of the cop spindles and movable in a direction to level a cop spindle in the magazine, of a transferrer adapted to transfer cop spindles from the magazine to the shuttle, and means operatively connected 45 with the transferrer to move the bar in one direction, and a spring to move it in the other direction.

4. In weft-replenishing mechanism for 50 looms, the combination of a cop spindle magazine having surfaces adapted to retain and guide the cop spindles by their heels substantially parallel to the axis of the shuttle, one of these surfaces being one surface of a bar engaging the heel ends of 55 the cop spindles and movable in a direction to level and thereby release any cop spindle which may be jammed in the magazine, means operative to move the bar longitudinally, and pivotal means connecting the lower back portion of the magazine to the upper portion thereof, whereby it is capable of swinging rearward when giving passage to a cop spindle.

5. In weft-replenishing mechanism for 60 looms, the combination of a cop spindle

magazine having surfaces adapted to retain and guide the cop spindles by their heels substantially parallel to the axis of the shuttle, one of these surfaces being one surface of a bar engaging the heel ends of the cop 70 spindles and movable in a direction to level a cop spindle in the magazine, a spring connected to the said bar to return it to normal position, a transferrer adapted to transfer cop spindles from the magazine to the shuttle 75 and means operatively connected with the transferrer to move the bar in opposition to the spring.

6. In weft-replenishing mechanism for 80 looms, the combination of a cop spindle magazine having surfaces adapted to retain and guide the cop spindles by their heels substantially parallel to the axis of the shuttle, one of these surfaces being one surface of a bar engaging the heel ends of the cop 85 spindles and movable in a direction to level a cop spindle in the magazine, a spring connected to the said bar to return it to normal position, a transferrer adapted to transfer cop spindles from the magazine to the shuttle 90 and means operatively connected with the transferrer to move the bar in opposition to the spring, pivotal means connecting the lower back portion of the magazine to the upper portion thereof whereby it is capable 95 of swinging rearward when giving passage to a cop spindle, a movable escapement adapted to release the cop spindles, one at a time from the magazine so that they can come successively under the influence of the trans- 100 ferrer and means connecting the transferrer and the escapement so that one will operate the other.

7. In weft-replenishing mechanism for 105 looms, the combination of a cop spindle magazine having its back lower portion which guides the cop spindle into the shuttle, pivoted relatively to the fixed portion of the magazine, said fixed and pivoted portions serving to retain and guide the cop 110 spindles before and during transfer by surfaces acting on the cylindrical surfaces and on the outer ends of the heels and on a reduced cylindrical surface adjoining the heels.

8. In weft-replenishing mechanism for 115 looms, a cop spindle magazine having the lower end of its back wall pivoted and having slots in the lower ends of its back and front walls to permit the passage of the 120 transferrer through the walls, the said trans- ferrer, the remaining portion of the lower ends of the magazine forming jaws shaped so as to retain and guide the cop spindle before and during transfer by surfaces acting 125 on the cylindrical surfaces and on the outer ends of the heels and on a reduced cylindrical surface adjoining the heels.

9. In weft-replenishing mechanism for 130 looms, a cop spindle magazine having the

lower end of its back wall pivoted and having slots in the lower ends of its back and front walls, to permit the passage of the transferrer through the walls, the said transferrer, the remaining portion of the lower ends of the magazine forming jaws shaped so as to retain and guide the cop spindle before and during transfer by surfaces acting on the cylindrical surfaces and on the outer ends of the heels and on a reduced cylindrical surface adjoining the heels, the back

pivoted jaws passing to one side of the front jaws.

In witness whereof we have hereunto set our hands in the presence of two witnesses. 15
